UNITED STATES PATENT OFFICE.

CHARLES L. JOHNSON, OF MORRISVILLE, PENNSYLVANIA.

SASH-LOCK.

1,205,212.

Specification of Letters Patent. Patented Nov. 21, 1916.

Application filed March 7, 1916. Serial No. 82,740.

To all whom it may concern:

Be it known that I, CHARLES L. JOHNSON, a citizen of the United States, residing at Morrisville, in the county of Bucks and 5 State of Pennsylvania, have invented new and useful Improvements in Sash-Locks, of which the following is a specification.

The invention relates to locks and latches and has for an object to provide a lock, particularly adaptable to window sashes and 10 the like, to secure one or a plurality of members against relative movement.

Among other features the invention comprehends a simple device, that can be easily 15 operated and which will insure an effective locking of one element or member relative to another and furthermore prevent any rattling of the locking element. To this end the invention is particularly adapted to 20 windows for locking the same against relative movement, the invention furthermore being neat and compact in appearance and easily applied to effect the desired purpose.

In the further disclosure of the invention 25 reference is to be had to the accompanying drawings, constituting a part of this specification, in which similar characters of reference denote corresponding parts in all the views and in which,

30 Figure 1 is a plan view of the lock, Fig. 2 is a vertical sectional view taken through the lock, on the line 2—2 in Fig. 1, the lock being shown in applied position, and Fig. 3 is a perspective view of the lock.

35 Referring more particularly to the views I provide an L shaped body 10, formed as it were of two plates 11, 12, the former having a raised portion 13, providing a chamber 14. The plate 12 has an opening 15 in which 40 is arranged to slide, a latch element 16, having a cross groove or depression 17 in one side and terminating at one end in a reduced stem 18, sliding in a bearing 19, rising from the raised portion 13 of the 45 plate 11. A helical spring 20 encircles the stem 18 with one end of the spring abutting against the bearing 19 and the other abutting against the latch element 16 at the inner end of the stem. A suitable thumb nut 21 50 is disposed in the chamber 14 and has a stem 22 journaled in the raised portion 13 and extending into the cross groove 17, a

circular disk 23 being carried in the end of the stem and offset thereon from the center of the disk to operate in the cross groove in 55 the nature of a cam. Suitable screws 24 are provided to pass through the plates 11, 12 and secure the described article to a sash 25 in a cut out portion 26 thereof, a keeper 27 having a depressed or recessed portion 28 60 for the reception of an end of the latch element 16, being secured to the member 29 by screws 30.

Referring now to the views it will be clearly seen that rotation of the thumb nut 65 21 will rotate the offset disk 23 in the cross groove 17, causing the former to engage end portions or walls 31 of the cross groove and thus slide the latch element 16 into or out of the depressed or recessed portion 28 of 70 the keeper 27, the latch element, when extending into the portion 28 being adapted to lock the sash 25, and member 29 against relative movement. The spring 20 is provided to prevent rattling of the latch element 75 28 and also causes one of the wall portions 31 to be in contact with the disk 23 at all times thus taking up any otherwise lost motion of the disk.

From the foregoing it will be seen that 80 the device described can be easily operated: will effectively accomplish the purpose for which it is designed and can be cheaply manufactured and easily assembled, consisting of few parts that cannot readily get 85 out of order or quickly wear out.

Having described my invention, I claim:—

A lock comprising an L shaped body providing a plurality of plates, one of which has an opening and the other a raised portion, 90 a grooved latch element slidable on the raised portion and having an end passing through the opening, a stem on the latch element, a bearing on the raised portion and having the stem journaled therein, a thumb nut in the raised portion, a stem on the nut and journaled in the raised portion, a cam on the stem and operable in the groove of the latch and a spring encircling the stem 95 to hold the latch element at all times in contact with the cam.

In testimony whereof I affix my signature.

CHARLES L. JOHNSON.
